UNITED STATES PATENT OFFICE.

GEORGE B. BOWELL, OF LONDON, ENGLAND, ASSIGNOR TO THE PEARSON FIRE ALARM LIMITED, OF LONDON, ENGLAND.

AUTOMATIC FIRE-ALARM SYSTEM.

No. 802,554.

Specification of Letters Patent.

Patented Oct. 24, 1905.

Application filed December 31, 1903. Serial No. 187,342.

To all whom it may concern:

Be it known that I, GEORGE BENNETT BOWELL, a subject of the King of Great Britain and Ireland, residing at 6 Scarsdale Villas, Kensington, London, England, have invented certain new and useful Improvements in Automatic Fire-Alarm Systems; and I do hereby declare the following to be a full, clear, and exact description of the invention, such as will enable others skilled in the art to which it appertains to make and use the same.

This invention for improvements in automatic fire-alarm systems relates to an alarm installation in a building which sends a fire-call to a central station when the local circuits are acted on by thermostats under the influence of heat and which also sends a different or trouble-call in case of a break in the wires connecting the thermostats within the building.

Figure 1 is a diagrammatic view of an apparatus embodying my invention. Fig. 2 is a similar view showing a modification.

The apparatus employed in the said installation comprises a pair of wires and a transmitter driven by clockwork and held by a catch controlled by an electromagnet. The transmitter with the code-message on its periphery is connected, together with the transmitters from other installations, into a main-line circuit and is provided with an auxiliary contact which renders the code inoperative after the first signal unless the thermostats have acted. Now according to this invention each installation is operated by current derived from the main-line circuit and is protected by open-circuit thermostats that are connected across the pair of wires within the building. The installation comprises a clockwork-transmitter, with code break-wheel, escapement-wheel, and an additional contact-wheel, an electromagnet controlling the escapement, and two relays.

In the accompanying diagram, M M show the main-line circuit. The transmitter T comprises the transmitting-disk or break-wheel b, on which bears the brush a, the escapement c d and the contact-disk g and contact-brush h. The contact-disk g is arranged to come into contact with brush h after the first revolution of wheel b and thereafter to remain in contact. It will be

understood that this mechanism is driven by 55 a mainspring and regulated as to its speed by the escapement, and to prevent the escapement from moving normally a detent j is provided, which is pulled back to free the escapement upon the energization of the magnet E and held back mechanically during the actual breaking between brush a and break-wheel b by the cam o and lever p. In series with these parts M a b T E, &c., is the relay R, and in shunt with the relay R is the 60 relay r; but this latter is connected, as shown in the diagram, through A and B, which are the wires throughout the installation and across which are connected the thermostats' contacts. The relay R operates a 65 contact s and the relay r a contact t. Contact t is connected, as shown, to short-circuit magnet E, and contact s is normally out of action, but can short-circuit brush a and break-wheel b after the first revolution of 70 wheel b—that is, upon the establishment of contact between g and h.

The action of the apparatus is as follows: Normally a portion of the main-line current by reason of the resistance of relay R is diverted through thermostat-wire B, relay r, and thermostat-wire A. This keeps contact t closed, and magnet E is not energized. Should a fire occur, and thus by means of any thermostat H short-circuit wires A and B, 80 then relay r will let go the contact t, and thus magnet E will be thrown into the main-line circuit and will attract the detent j and allow the clockwork to start. There will be no current through the circuit g h i s, since 85 owing to the contact between wires A and B the current will pass this way, and the relay R will be unable to attract its armature, or if armature should have been previously in the near position it will be unable to retain 90 it, because the difference of potential across relay R will have been lowered almost to nothing. Hence the break-wheel b will signal its code several times, and this is known 95 in the central office as a "fire-call." Now, if, 100 on the other hand, either or both wires A B become disconnected then the effect is as follows: Relay r will let go its armature, and this action insures the release of the clockwork by cutting magnet E into the main-line circuit; but since circuit of wire A, relay r, and wire B is cut out the current through 105 relay R is very much increased, and this in-

- sures contact *s* becoming closed even if it were not closed before. Hence the break-wheel *b* is only allowed to signal during its first revolution, because it is afterward short-circuited through *s i h g*, and such a signal—that is, the code-number transmitted once only—is known in the central office to mean that such and such an installation is out of order and must receive prompt attention.
- 10 In a modified method of working we may connect the contact of relay *R* to the junction of *E* and *B* instead of to the terminal *M*, as shown, and provide additional gaps in the cam *o*. The action is then precisely the same, except that in the case of a break in the circuit of wires *A* and *B* the transmitter *b* only makes one revolution, the second and subsequent signals being prevented by stopping the motion of the transmitter instead of by allowing it to rotate short-circuited. An apparatus illustrating such modification is illustrated at Fig. 2.
- What I claim, and desire to secure by Letters Patent, is—
- 25 1. In a thermostatic fire-alarm system, the combination with a transmitter, a main circuit, a branch of the main circuit and an electromagnet, of a main relay arranged as a shunt to the branch circuit, a local relay in the branch circuit, open-circuit thermostats
- 30

across the branch circuit as shunts to the relays, a switch normally short-circuiting the electromagnet and adapted to be operated by the local relay, a switch operated by the main relay and adapted to stop the action of the transmitter, and an open switch in the short circuit of the transmitter and adapted to be closed by the transmitter at the end of the first round.

2. In a thermostatic fire-alarm system, the combination with a transmitter, a main circuit, a branch of the main circuit and an electromagnet, of a main relay arranged as a shunt to the branch circuit, a local relay in the branch circuit, open-circuit thermostats across the branch circuit as shunts to the relays, a switch normally short-circuiting the electromagnet and adapted to be opened by the local relay, a switch operated by the main relay to short-circuit the transmitter, and an open switch in the short circuit of the transmitter adapted to be closed by the transmitter at the end of the first round.

In testimony whereof I have affixed my signature in presence of two witnesses.

GEORGE B. BOWELL.
